UNITED STATES PATENT OFFICE.

FRITZ JOHNSON, OF RACINE, WISCONSIN, ASSIGNOR TO JOHNSON COMBINED PRESSING & REFINISHING IRON COMPANY, OF RACINE, WISCONSIN, A CORPORATION OF WISCONSIN.

FLAT-IRON.

1,092,839.

Specification of Letters Patent. Patented Apr. 14, 1914.

Application filed February 13, 1913. Serial No. 748,268.

To all whom it may concern:

Be it known that I, FRITZ JOHNSON, a citizen of the United States, residing at Racine, in the county of Racine and State of Wisconsin, have invented certain new and useful Improvements in Flat-Irons, of which the following is a specification, reference being had to the accompanying drawing, forming a part thereof.

10. This invention relates more particularly to gas heated flat irons.

The main objects of the invention are to effect a thorough and uniform mixture of air with the gas just before it issues from 15 the burner jets or apertures and is burned and thus to insure more perfect combustion and greater economy in the consumption of gas, avoiding smoke and odor; to prevent overheating the side walls of the iron and 20 scorching fabrics accidentally coming in contact therewith; to facilitate removing and replacing the cover for the purpose of cleaning, repairing or inspecting the burner and combustion chamber or internal parts 25 of the iron; and generally to simplify and improve the construction and operation of flat irons of this class.

In the accompanying drawing like characters designate the same parts in the several figures.

Figure 1 is a vertical longitudinal section on the line 1—1, Fig. 2, of a flat iron embodying the invention; Fig. 2 is a horizontal section on the line 2—2, Fig. 1; and 35 Fig. 3 is a vertical cross section on the line 3—3, Fig. 1.

The iron comprises three main parts or sections, a base *a*, a body and burner section *b*, and a cover and handle section *c*. 40 The base *a* is formed with an upwardly projecting marginal flange *d* and with a central and vertical threaded socket *e*. The body and burner section *b* has double or outer and inner walls *f* and *g*, forming an 45 air and gas mixing and an insulating chamber *h*, surrounding a combustion chamber *i*, and extending from the junction of the body section *b* with the base *a*, nearly to the cover and handle section *c*. The section *b* is 50 fitted and seated on the top of the flange *d*, which it overhangs on the inner side, and is formed in the lower part thereof over-

hanging the base, with downwardly directed jet apertures *j*. Air inlet openings *k* are formed in the walls of the iron adjacent 55 to the jet apertures *j*, for supplying air to the combustion chamber and insuring perfect combustion of the mixture of gas and air as it issues from the jet apertures *j*. These openings are preferably formed as 60 shown, partly in the base *a* and partly in the section *b*, but they may be formed entirely in either of said parts. At the ends of the iron, which is preferably of lenticular shape in cross section as shown in Fig. 2, 65 the section *b* is formed at the top with raised bearings *l*, on which the cover and handle section *c* is removably seated, openings *m* on each side of the iron for the escape of the products of combustion of the 70 burner from the top of the combustion chamber *i*, being thus provided.

The section *b* is formed or provided with a bridge or cross piece *n*, which is centrally perforated in alignment with the socket *e* in 75 the base, and the several sections of the iron are connected and secured together by a single bolt *o*, threaded in said socket and bridge piece, and provided with a lock nut *p* for securing it in place in the bridge piece. The section *b* is formed or provided 80 on the under side with lugs *q*, which fit into the internal angles in the base flange *d* at the ends of the iron and hold the sections in proper relation to each other when they are 85 fastened together by the bolt *o*, as shown in Figs. 1 and 3. The bolt *o* extends above the lock nut *p* and is provided at its upper end with a cross head *r*, the overhanging ends of which are formed on the under side with 90 opposite inclines, as shown in Fig. 1.

The cover and handle section *c* consists of two spaced parallel plates *s* and *t*, which are secured to each other and to the handle frame *u* by screws *v*. The plate *t* is formed 95 with threaded bosses for the screws *v* and at the ends with upwardly projecting flanges or bearings *w*, for supporting the plate *s* at a distance above it and forming an insulating and ventilating space between 100 the plates to keep the handle cool. The lower plate *t* is also formed with openings *x*, adjacent to its ends and on the under side with lugs *y* which fit into sockets in

the bearings *l* to hold the cover and handle section *c* and the body and burner section *b* in proper relation to each other when they are secured together by the bolt *o*.

- 5 A flanged locking piece *z*, fitted to turn in a central opening in the plate *t* and held in place by its flange between the plates *s* and *t*, is formed with an elongated slot 2, to pass over the head *r* on the bolt *o* and 10 permit the upper face of the locking piece to be turned into engagement with the inclines on the under side of the overhanging ends of said head, as shown by the drawing. The locking piece is provided with an 15 arm or handle 3, which projects laterally between the plates *s* and *t* to one side of the cover section, and affords convenient means for turning the locking piece. The top plate *s* of the cover section is formed with a 20 transverse slot to receive the head *r* when the parts of the iron are assembled, as shown in Figs. 1 and 3. The body and burner section *b* is provided at one end with the usual gas and air supply connection, consisting of 25 a tube 4 threaded or otherwise secured at one end in a boss on the section *b*, in communication with the chamber *h* and provided at its other end with a nipple 5 for the attachment of a gas supply hose, and 30 adjacent thereto with air inlet openings 6.

In the operation of the iron the gas and air supplied thereto through the tube 4 are checked in their flow through the chamber *h* and are heated or warmed by contact with 35 the wall *g* and expand, so that when the mixture issues from the jet apertures *j* it burns with a hot blue flame, which is projected downward against the bottom of the base. The cool air entering the chamber *h* 40 with the gas through the tube 4, circulating in said chamber around the iron, prevents the outer wall *f* of section *b* from being overheated and scorching articles coming in contact therewith, said chamber thus serving 45 the two-fold function of a mixing and expanding chamber for thoroughly mixing and warming the gas and air, and an insulating chamber separating the outer wall *f* from the inner wall *g* and thus preventing the outer wall from becoming sufficiently heated to scorch clothing or other fabrics 50 coming in contact with it. By turning the arm or handle 3 into the position indicated by dotted lines, Fig. 2, the slot 2 in the 55 locking piece *z* is brought into register with the cross head *r*, and the cover and handle section *c* may then be removed from the body and burner section, affording access to the combustion chamber and interior parts 60 of the iron for cleaning, repairing or inspecting the same. Broken or defective parts of the iron may be readily replaced by unscrewing the bolt *o* which connects the

base *a* and section *b* from the socket *e* in the base, or by removing the screws *v* which connect the plates *s* and *t* and the handle frame *u*.

Various changes in minor details of construction and arrangement of parts may be made without departure from the principle 70 and scope of the invention.

I claim:

1. A flat iron having an outer double wall forming an air and gas mixing and an insulating chamber surrounding the combustion 75 chamber and extending substantially from the bottom portion of the combustion chamber to its top, said mixing and insulating chamber having jet apertures in the lower part thereof and a gas and air supply connection.

2. In a flat iron the combination of a base having an upwardly projecting marginal flange, a double walled body and burner section seated upon and overhanging said flange 85 on the inner side thereof and forming a mixing and insulating chamber surrounding a combustion chamber substantially from its bottom portion to its top and having downwardly directed jet apertures in the lower 90 overhanging part thereof inside of said flange, and a gas and air supply connection.

3. In a flat iron the combination of a base section having a central screwthreaded socket, a hollow body and burner section 95 seated on the base section and having a centrally perforated bridge piece spanning the opening between opposite walls of the iron, and a single connecting bolt passing through said bridge piece and threaded in said socket. 100

4. In a flat iron the combination of a base section having an upwardly projecting marginal flange and a central threaded socket, a hollow body and burner section seated on said flange and having a centrally perforated 105 bridge piece spanning the space between opposite walls of the iron, a cover section removably seated on the top of said body and burner section and provided with a handle, and a single bolt threaded in said socket, 110 passing upwardly through and secured in said bridge piece, the cover being provided with means for detachably securing it to the upper end of said bolt.

5. In a flat iron the combination of a base section, a hollow body and burner section seated thereon, a bolt securing said sections together and having a head at its upper end, and a cover removably seated on said body and burner section and having a locking 120 piece movable into and out of engagement with the bolt head.

6. In a flat iron the combination with a hollow body section having an upwardly projecting bolt or stud provided at its upper 125 end with a cross head having opposite in-

clines on the under side of its overhanging ends, a cover and handle section removably seated on said body section, and a locking piece swiveled in said cover and handle section and slotted to pass over the head on said bolt or stud and to engage with the inclines on the under side of the head.

In witness whereof I hereunto affix my signature in presence of two witnesses.

FRITZ JOHNSON.
